US00D654970S

(12) United States Design Patent
Daves

(10) Patent No.: US D654,970 S
(45) Date of Patent: * Feb. 28, 2012

(54) FITNESS DEVICE

(76) Inventor: Bret Daves, Ankeny, IA (US)

() Term: 14 Years

(21) Appl. No.: 29/384,068

(22) Filed: Jan. 26, 2011

(51) LOC (9) Cl. 21-02

(52) U.S. Cl. D21/662

(58) Field of Classification Search D21/662,
D21/679, 680, 684, 686, 692, 694, 805; 482/91,
482/92, 95, 96, 104-110, 112, 127, 132,
482/140, 141, 148; D24/200, 211; 601/120

See application file for complete search history.
